CLAIM

The ornamental design for a personalized heart shaped picture frame, as shown and described.

DESCRIPTION

FIG. 1 is a perspective view of the front side of the invention.

FIG. 2 is a plan view of the front side of the invention.

FIG. 3 is a right side elevation view of the invention.

FIG. 4 is a front side elevation view of the invention; and, FIG. 5 is a cut-away view through the picture retaining opening in the heart shaped portion.

The rear and left elevations are the same as the respective opposite elevations and have no ornamentation.

The back has no ornamentation.

The broken lines are for environmental purposes only and form no part of the claimed design.
